(57) **CLAIM**

The ornamental design for the display screen or portion thereof with a graphical user interface, as shown and described.

DESCRIPTION

FIG. 1 is a front view of first image in a sequence for a display screen or portion thereof with a graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a fourteenth image thereof;

FIG. 15 is a front view of a fifteenth image thereof;

FIG. 16 is a front view of a sixteenth image thereof;

FIG. 17 is a front view of a seventeenth image thereof;

FIG. 18 is a front view of an eighteenth image thereof;

FIG. 19 is a front view of a nineteenth image thereof;

FIG. 20 is a front view of a twentieth image thereof;

FIG. 21 is a front view of a twenty-first image thereof;

FIG. 22 is a front view of a twenty-second image thereof;

FIG. 23 is a front view of a twenty-third image thereof;

FIG. 24 is a front view of a twenty-fourth image thereof;

FIG. 25 is a front view of a twenty-fifth image thereof;

FIG. 26 is a front view of a twenty-sixth image thereof; and,

FIG. 27 is a front view of a twenty-seventh image thereof.

The appearance of the images sequentially transitions through FIGS. 1-27. The process or period through which one image transitions to another forms no part of the claimed design. The broken lines illustrate portions of the graphical
